UNITED STATES PATENT OFFICE.

PAUL A. FRANK, OF AKRON, OHIO.

COMBINED SPARK-PLUG AND PRIMING DEVICE.

1,267,203.

Specification of Letters Patent. Patented May 21, 1918.

Application filed November 12, 1917. Serial No. 201,557.

To all whom it may concern:

Be it known that I, PAUL A. FRANK, a citizen of the United States, residing at Akron, in the county of Summit and State of Ohio, have invented certain new and useful Improvements in Combined Spark-Plug and Priming Devices, of which the following is a specification.

My invention relates to a combined spark plug and priming device, for use in connection with internal combustion engines.

An important object of the invention is to provide a device of the above mentioned character, which is simple in construction, inexpensive to manufacture, and convenient in use.

Other objects and advantages of the invention will be apparent during the course of the following description.

20 In the accompanying drawings forming a part of this specification and in which like numerals are employed to designate like parts throughout the same,

Figure 1 is a side elevation of apparatus embodying my invention,

Fig. 2 is a central longitudinal sectional view through the same,

Fig. 3 is a side elevation of a valve and associated elements, and,

30 Fig. 4 is a transverse sectional view taken on line 4—4 of Fig. 3.

In the drawings, wherein for the purpose of illustration is shown a preferred embodiment of my invention, the numeral 5 designates a metallic tubular body portion of the device, the upper end of which is formed polygonal in cross-section, as shown at 6, for the reception of a wrench. The lower end of the tubular body portion 5 is cylindrical and is exteriorly screw-threaded, as shown at 7, to engage within the spark plug opening of the cylinder of the engine.

Arranged within the tubular body portion 5 is a tubular insulating member or porcelain insulator 8, having a longitudinal bore 9. The insulating member 8 is provided with an annular flange 10, adapted to engage a shoulder 11, and a clamping ring 12, having screw-threaded engagement with the upper end of the tubular body portion 5, as shown.

The numeral 13 designates an open ended or cup-shaped priming receptacle, which is preferably metallic and formed integral with a base 14. This base is provided at its

lower end with an annular groove 15, for the reception of the upper end of the tubular insulating member 8. The base 14 carries an annular flange 16, the end of which is bent or spun into an annular groove 17, formed in the insulating member 8, whereby the priming receptacle 13 is rigidly attached to the insulating member.

Extending laterally from the base 14 is a metallic arm 18, provided with a binding post 19, for connection with one pole of a source of current, the opposite pole of which is grounded to the frame work of the engine, and accordingly has electrical connection with the metallic tubular body portion 5, as is well known.

The base 14 is provided with a conical or tapered opening 20, leading into the priming receptacle 13, and into a cylindrical opening 21, which is internally screw-threaded, as shown. The opening 21 leads into the bore 9 of the insulating member 8.

The wall of the opening 20 constitutes a valve seat for a conical or tapered valve 22, carried by a valve rod 23, extending upwardly beyond the receptacle 13, and provided with an insulating handle 24. Beneath and adjacent the valve 22 the rod 23 is provided with an enlarged cylindrical screw-threaded portion 25, engaging within the screw-threaded opening 21. This screw-threaded portion 25 is provided with longitudinal surface grooves or passages 26, preferably U-shaped in cross-section, as shown in Fig. 4. The rod 23 projects downwardly beyond the screw-threaded portion 25 in the form of an electrode 27, extending through the bore 9, and projecting below the screw-threaded portion 7 of the tubular body portion 6, to be arranged in proximity to an approximately U-shaped co-acting electrode 28, attached to the screw-threaded portion 7, as shown.

In operation, when the handle 24 is turned clockwise the screw-threaded portion 25 is screwed down to bring the valve 22 in contact with its valve seat 20, thus closing the upper end of the bore 9. It is obvious that the device will now function as the ordinary spark plug.

To prime the engine before starting, the handle 24 is turned counter-clockwise, to elevate the valve 22 from its valve seat 20, whereby the passages 26 place the interior of the priming receptacle 13 in communica-

tion with the bore 9. The gasolene or like fuel is now supplied to the receptacle 13 and will pass into the cylinder of the engine. Before starting the engine, the valve 5 22 is returned to its seat.

It is to be understood that the form of my invention herewith shown and described is to be taken as a preferred example of the same, and that various changes in the shape, 10 size, and arrangement of parts may be resorted to without departing from the spirit of the invention or the scope of the subjoined claims.

Having thus described my invention, I 15 claim:

1. A combined spark plug and priming device, comprising a tubular metallic body portion; a tubular insulator arranged therein; a metallic priming receptacle secured to 20 the tubular insulator and having a screw-threaded opening adapted for communication with the bore of the tubular insulator; a rod extending longitudinally through the bore and having one end serving as an electrode; a coacting electrode carried by the tubular metallic body portion; a cylindrical screw-threaded member carried by the rod and engaging within the screw-threaded 25 opening and having a longitudinal passage formed therein; a valve arranged above the screw-threaded member and carried by the rod to cover and uncover the opening;
2. A combined spark plug and priming device, comprising a tubular metallic body portion exteriorly screw-threaded for engagement within the screw-threaded opening of the cylinder of an engine; a tubular insulator secured within the tubular metallic body portion and projecting above the same; a metallic priming receptacle having a depending flange receiving the upper end of the tubular insulator and secured thereto, 30 said priming receptacle being provided in its bottom with a valve seat and a screw-threaded opening having communication with the bore of the tubular insulator; and a rod extending longitudinally through the tubular insulator and provided near its upper end with a valve to engage the valve seat and beneath the valve with a screw-threaded portion to engage within the screw-threaded opening, said screw-threaded portion having its side shaped to provide a passage, one end of the rod being 35 arranged in proximity to the tubular metallic body portion to function as an electrode.

In testimony whereof I affix my signature in presence of two witnesses.

PAUL A. FRANK.
